COVER AND MOUNTING FOR VENTS AND
THE LIKE

Duncan J. McIntyre, Syracuse, N. Y.

Application October 25, 1937, Serial No. 170,977

8 Claims. (Cl. 182—31)

This invention appertains to vent constructions, and more especially, to covers and mountings therefor to be used with air inlets of sewer laterals which include a main house trap.

5 The primary object of the invention is to provide an improved vent cover and mounting of simple, compact and rugged construction, which includes provision for preventing the entrance of sticks, stones and other foreign matter which 10 would tend to clog the vent and/or house trap if permitted to enter the vent pipe.

Another object of the invention is to provide 15 a means for facilitating the mounting of the vent cover on the vent pipe in such position that the vent cover is normally spaced a predetermined distance from the end of the vent pipe, thereby positively assuring the free entrance of air through the vent cover into the vent pipe.

Still another object of the invention is to provide 20 means for reinforcing the vent cover against forces tending to crush the same against the upper end of the vent pipe, and in its preferred embodiment, I attain this end by the same means which serves to normally space the vent cover 25 from the end of the vent pipe, as previously referred to.

In preventing sticks and stones from entering 30 into the vent pipe through the vent cover, I preferably employ a plurality of baffle bars depending from the bottom side of the vent cover and having oppositely inclined laterally projecting surfaces arranged at different elevations relative to and below the usual elongated slots formed in the cover plate, such arrangement affording a maximum 35 degree of protection against the passage of sticks and stones through the vent cover, while at the same time assuring compactness of form with a minimum degree of obstruction of the passage of air through the cover plate.

40 Other and further objects and advantages of the invention will be hereinafter described and the novel features thereof defined by the appended claims.

In the drawings:

45 Figure 1 is a top plan view of a vent cover constructed according to my invention;

Figure 2 is a transverse sectional view taken approximately on the line 2—2 of Figure 1;

Figure 3 is a top plan view of a collar constituting a mounting for the vent cover shown in Figures 1 and 2; and

Figure 4 is a fragmentary vertical sectional view illustrating the application of the mounting collar and vent cover to the upper extremity of 55 a conventional vent pipe.

Like reference characters designate corresponding parts in the several figures of the drawings.

In the usual plumbing system, the waste matter is ordinarily conducted through a lateral conduit running below ground from the building to the sewer main which is normally located in the street below the street level. It has been the common practice to provide a main trap intermediate the sewer main and the building, such trap 5

being vented by extending a vent pipe upwardly from the trap to the ground level, or to a point slightly above the ground level. This vent pipe ordinarily is located so that it projects upwardly through the sidewalk, or at some point between 10 the sidewalk and the curb line. Generally, the arrangement is prescribed by sanitary regulations or codes, and these regulations or codes ordinarily

require the use of a vent pipe having a diameter of at least four inches, and a cover for the upper 15 end of the vent pipe which is so constructed as to provide an air space through which air may enter the vent pipe, and the area of which air space is not less than the area of the four inch vent pipe. I am aware that various vent pipe 20

covers fully complying with these regulations have been employed, and in many instances, provision has been made to prohibit the entrance of sticks, stones and other foreign matter into the 25 vent pipe through the cover. In these latter 30 cases, however, the covers have not proven to be practical largely because of their complicity and/or increased cost. I am not aware of any

type of cover having provision for preventing the 35 passage of sticks and stones therethrough, which would fulfill the usual requirement for the free 40 passage of air therethrough without necessarily substantially increasing the size of the cover over and above the standard sizes commonly employed without regard to the clogging protection feature 45

above referred to. Size is, of course, of considerable importance in devices of this kind, since the appearance, strength, cost, etc. are directly affected thereby. The larger the size of the cover, the more unsightly it becomes, having in mind that 50

the covers are exposed to view. Moreover, if the vent pipe projects above the ground level, as many times is the case, a large cover would increase the hazard produced thereby through reason of creating a stumbling block over which children or pedestrians might trip.

Referring now to Figures 1 and 2 of the drawings, I designates generally my improved vent cover which preferably has the form of a circular plate having a plurality of elongated slots 55

2 formed therein in spaced relation to each other and running substantially parallel across the plate. As in the usual vent cover, these slots 2 are of sufficient size that the total area thereof 5 is at least as great as, if not greater than, the cross-sectional area of a standard four inch vent pipe. At diametrically opposite points in the cover plate 1, I provide apertures 3, 3 for the reception of suitable fastening means such as 10 screws 4, 4 which serve to secure the cover plate 1 to its mounting, generally designated 5, and by means of which the cover plate is mounted on the upper end of the vent pipe, generally designated 6, as shown in Figure 4.

15 Between the slots 2 in the cover plate 1, the material of the cover plate, which is preferably composed of metal, has the form of bars 7, thus forming a grate-like structure. Depending from the lower side of the cover plate 1, and preferably formed integrally with the bars 7, I provide a plurality of ribs or webs 8, which project downwardly therefrom substantially normal to the plane of the cover plate. The lower extremity of each rib or web 8 is enlarged, as at 9, so that it 25 has a generally triangular-shaped cross-section, thus providing laterally projecting, oppositely inclined baffle surfaces 10 and 11 at the respectively opposite sides of the ribs or webs 8. As best seen in Figures 2 and 4, the baffle surfaces 10 and 11 are substantially spaced below the slots 2 in the cover plate 1, and each baffle surface extends laterally substantially to a point below the center of the slot 2 lying above the same, or about midway to the next rib.

35 In order to permit air to enter the slots 2 and pass freely downwardly therethrough between the ribs or webs 8 and around the baffle surfaces 9 and 10, the ribs or webs 8 are preferably of different heights, thus disposing the baffle surfaces 10 and 11 at the lower extremities of the respective ribs or webs 8 at different elevations. As shown in Figures 2 and 4, the central rib or web 40 extends substantially below each of the others, and the ribs at respectively opposite sides thereof 45 are progressively shorter in height. Thus the space 12 between any two adjacent baffle surfaces 10 and 11, and between the respective baffle surfaces and their nearest rib or web 8, is preferably not appreciably less than the width of each slot 50 2, thus permitting the free passage of air through the slots 2 and downwardly past the baffle surfaces without substantial obstruction or interference with such free flow. As shown in the drawings, the construction of the vent cover 55 described above is the same at one side of a plane passing vertically through the center of the cover as at the other side, so that the ribs and the baffle surfaces formed at the lower extremities thereof are arranged in pairs, the corresponding 60 ribs of each pair being respectively located at opposite sides of the center of the plate, and the pairs of ribs depending different distances below the cover plate. As will be best understood from reference to Figure 1, the ribs or webs 8 run 65 lengthwise of the bars 7 of the cover plate, but terminate at their opposite extremities somewhat inwardly of the periphery of the cover plate. The cover plate is preferably constructed as a one-piece casting of brass, aluminum, iron or other 70 metal, but it is to be understood that I do not wish to be limited to any particular material since the material may be varied as circumstances require or permit.

To facilitate the mounting of the cover plate 75 1 on the upper end of a vent pipe, I preferably

provide a mounting collar 5 having a form which will be best understood from reference to Figures 3 and 4. The head 13 of the mounting collar 5 is provided with an annular recess 14 in its upper face in which the cover plate 1 is adapted to be seated. The depth of the recess is approximately equal to the thickness of the cover plate, so that when the latter is seated in the recess, the upper face of the cover plate will lie flush with the upper end of the mounting collar 5. Inwardly projecting 10 diametrically opposed lugs or bosses 15, 15 are provided within the head 13 of the mounting collar 5, and these bosses have tapped openings 16, 16 to receive the fastening screws 4, 4 which serve to secure the cover plate 1 to the mounting 15 collar, as will be best understood from reference to Figure 4. The heads of the fastening screws 4, 4 are preferably countersunk in the cover plate 1 so that the entire assembly will present a perfectly flat smooth surface at its upper end. 20

Depending below the head 13 of the mounting collar 5, is a sleeve or skirt 17 having a diameter somewhat larger than the diameter of a standard vent pipe generally designated 6 in Figure 4. The lower extremity 18 of the sleeve or skirt 17 is preferably turned inwardly for a purpose which will hereinafter more fully appear. As in the case of the cover plate 1, the mounting collar 5 is preferably composed of a one-piece metal casting, the head 13 of which is tapered downwardly and inwardly so as to merge with the integral skirt or sleeve 17. 25

In applying the mounting collar 5 to the vent pipe 6, the sleeve or skirt 17 is slipped over the end of the vent pipe far enough to cause the lower face of the central rib 8 of the cover plate 1 to abut against the upper edge of the vent pipe when the cover plate is secured in position on the upper end of the mounting collar. In practice, the cover plate 1 is applied onto the mounting collar 5 before the mounting collar is slipped onto the vent pipe 6, and as the skirt or sleeve 17 of the mounting collar is slipped onto the vent pipe, the central rib 8 of the cover plate will act as a gauge through its abutting engagement with the upper edge of the vent pipe across which the rib extends diametrically. Thus, the central rib positively prevents the mounting collar 5 from being moved down too far on the end of the vent pipe, and assures the proper positioning of the 40 collar on the vent pipe. When the collar has been positioned as just described, the cover plate 1 may then be removed to permit the collar to be sealed around the upper end of the vent pipe. Any suitable packing material may be employed 45 to establish this seal, but I preferably pour molten lead between the skirt or sleeve 17 and the vent pipe, as indicated at 19 in Figure 4. After the molten lead has cooled and hardened, the mounting collar 5 will be rigidly secured to the vent pipe, and all that is necessary to be done to complete the installation of the vent cover is to apply the cover plate 1 to the upper end of the collar and fasten the same to the collar by means of the screws 4, 4. When the cover plate 1 is so mounted, the lower end of the central rib 8 will bear upon the upper edge of the vent pipe 6. This arrangement has a distinct advantage, especially when the upper face of the cover plate 1 and mounting collar 5 are set flush in the ground or 50 pavement where heavy bodies such as trucks or other vehicles may run over the same. Should a heavy weight be imposed upon the upper end of the mounting collar 5 or upon the upper face of the cover plate 1, the packing 19 would be 55

loosened from the outer face of the vent pipe 6 or from the inner face of the skirt or sleeve 17, and the mounting collar 5 would be forced down onto the end of the vent pipe excepting for the fact 5 that this is effectively prevented by reason of the abutting engagement of the lower end of the central rib 8 with the upper edge of the vent pipe 6. Moreover, in addition to more effectively sustaining heavy weights which may be imposed 10 upon the vent cover, thereby eliminating the likelihood of breaking the seal between the skirt of the mounting collar and the vent pipe, breaking or crushing of the cover plate 1 is minimized through reinforcement of the cover plate which 15 is afforded by the plurality of ribs 8, and particularly, by the central rib which bears on the upper end of the vent pipe 6. I have found that my vent cover is better able to withstand crushing forces, and there will be considerably less break- 20 age of the cover plates than is the case where the ordinary vent covers of the plain slotted or perforated plate type are employed. This feature alone is of great importance, and the utility and advantages of my improved vent cover are 25 further enhanced by the employment of the baffle surfaces 10 and 11 formed at the lower extremities of the ribs 8, and which are so arranged as to prevent the insertion by mischievous children of sticks, stones and other foreign matter 30 through the vent cover, while at the same time affording a passage of a size equal to the full area of the vent pipe for the free circulation of air through the vent cover. Not only does the vent cover prevent deliberate or purposeful attempts 35 to insert sticks, stones and the like through the vent cover and into the vent pipe, but it also prevents such materials from gaining access to the vent pipe by accident or otherwise, as where the vent cover becomes submerged due to a heavy 40 rain, or melting snow or ice. In fact, my invention may be effectively used as a drain cover, in which case water or other fluids may freely flow through the cover plate while prohibiting the entrance of solids which would tend to clog up 45 the drain.

While the specific details have been herein shown and described, the invention is not confined thereto, as changes and alterations may be made without departing from the spirit thereof 50 as defined by the appended claims.

Having thus described my invention, what I claim as new and desire to secure by Letters Patent is—

1. In a device of the class described, a collar member having a diameter somewhat greater than the diameter of a vent pipe or the like and adapted to be mounted thereon, a cover member adapted to be positioned across the open end of the collar member, said cover member having a 55 plurality of openings therein arranged in spaced relation to each other and forming bars therebetween constituting a grate-like structure, and ribs depending from the bars aforesaid and each terminating at its lower extremity in the form 60 of an enlargement substantially triangular in cross-section with two of the vertices respectively disposed at opposite sides of the center of the rib and in the same plane, whereby to form oppositely inclined baffle surfaces extending laterally in opposite directions from each rib.

2. A device as claimed in claim 1, wherein the

ribs terminate at different distances below the cover member.

3. A device as claimed in claim 1, wherein the ribs progressively terminate at different distances below the cover member with the highest rib 5 disposed substantially at the center of the cover member.

4. In a device of the class described, a collar member having a diameter somewhat greater than the diameter of a vent pipe or the like and 10 adapted to be mounted thereon, a cover member adapted to be positioned across the open end of the collar member, said cover member having a plurality of substantially parallel slots therein extending transversely across the cover member 15 with their opposite ends terminating adjacent to the periphery of the cover member, said slots forming bars therebetween constituting a grate-like structure, and ribs depending from the bars aforesaid and terminating at their lower extremities in the form of enlargements substantially triangular in cross-section whereby to form oppositely inclined baffle surfaces extending laterally in opposite directions from each rib, the baffle surfaces aforesaid being spaced below the 20 slots and terminating laterally substantially midway between the ribs and in spaced relation to the contiguous baffle surfaces whereby to provide a space therebetween at least as great as the area 25 of the slots. 30

5. The combination with a vent pipe or the like, of a collar member having a larger diameter than the vent pipe and adapted to be mounted thereon and around the exterior of the end of the vent pipe, a cover member having a plurality of openings therein adapted to be positioned across the open end of the collar, and means depending from the lower side of said cover member for abutting engagement with the end of said vent pipe. 35

6. The combination with a vent pipe or the like, of a collar member having a larger diameter than the vent pipe and adapted to be mounted thereon, a cover member having a plurality of openings therein adapted to be positioned across the open end of the collar, and means depending from the lower side of said cover member for engaging the end of said vent pipe, said last named means comprising a rib arranged normal to the plane of the cover member and extending transversely 45 thereacross and within the collar member. 50

7. A device as claimed in claim 1, wherein the ribs terminate in pairs different distances below the cover member, one rib of each pair being located at the opposite side of a vertical plane passing through the center of the cover member from the corresponding rib of the same pair. 55

8. A cover for vent pipes and the like, comprising a plate having a plurality of spaced substantially parallel slots provided therein and forming bars therebetween constituting a grate-like structure, ribs depending from the lower side of the bars aforesaid and terminating at different distances therebelow, the lower extremity of each rib being provided with oppositely inclined 60 laterally projecting baffle surfaces terminating substantially midway between the ribs and forming passages therebetween, the total area of which is substantially equal to the combined areas of 65 the slots. 70
